CLAIM

The ornamental design for a solar roof for golf cart as shown and described.

DESCRIPTION

FIG. 1 is a front perspective view of the solar roof for golf cart showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a front perspective view thereof, shown in environmental use.

The broken lines shown in the figures are for the purpose of illustrating portions of the solar roof for golf Cart form no part of the claimed design. The broken line showing of the cart in FIG. 8 illustrates environmental structure and forms no part of the claimed design.
